(57) CLAIM

The ornamental design for an accessory for notebook computer, as shown and described.

DESCRIPTION

FIG. 1 is a perspective view of an accessory for notebook computer showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a reference view thereof showing a mouse put in the accessory.

The broken lines illustrate portions of the accessory for notebook computer that form no part of the claimed design.
